Application September 4, 1956, Serial No. 607,828

5 Claims. (Cl. 271—87)

This invention pertains to apparatus for handling sheet material, and more particularly, to a machine for receiving a succession of bags or sheets and arranging them in an orderly group or stack.

One object of the present invention is to provide a novel and efficient machine for stacking bags made of sheet material such as cellophane or the like.

Another object of the present invention is to provide an improved mechanism adapted to receive bags presented to it successively and to arrange them in stacked relation.

Another object is to provide a mechanism for stacking sheet material articles presented successively thereto and for arranging them in groups each of which contains a predetermined number of the articles.

Another object is to provide a stacking machine adapted to handle sheet material articles in a wide variety of sizes without requiring adjustment.

These and other objects and advantages of the invention will become apparent from the following description and the accompanying drawings, wherein:

Fig. 1 is a side elevation of the stacking device of the present invention.

Fig. 2 is a rear elevation of the device shown in Fig. 1. Fig. 3 is a section taken along line 3-3 of Fig. 1.

Figs. 6, 7 and 8 are fragmentary sections similar to Fig. 5 illustrating successive stages of the transference of a base from one liquid to another.

Fig. 9 is a fragmentary section illustrating the mechanism for releasing the bags or sheets at the end of the cycle.

Fig. 10 is a fragmentary perspective of one of the

Fig. 10 is a fragmentary perspective of one of the gripping units of the stacking machine of the invention.

Fig. 12 is a section taken along line 12—12 of Fig. 11.

For the purposes of illustration, the stacking machine

of the present invention is disclosed in connection with a bag making machine of the type shown in the United States patent application Serial No. 310,637, filed September 20, 1952, by Harry A. Mead, entitled "Automatic Bag Making Machine," now Patent No. 2,762,271, issued September 11, 1956, and reference is made to said patent for the details of the bag making machine. It should be noted, however, that the stacking machine of the present invention is adaptable for use with other types of bag making machines, or, in fact, with any type of machine which is adapted to feed bags or sheets successively to the stacking machine.

As shown in Fig. 4, the bag making machine comprises a conveyor A (corresponding to the conveyor 14 of said Patent No. 2,762,271) which carries tubular bag blanks from a cutting mechanism (not shown) to heat sealing units B on a rotatable drum C (corresponding

to the heat sealing units 42 on the drum 21 of said Patent No. 2,762,271), whereby the bottoms of the bags are sealed as the drum rotates through approximately 180°. After the bottoms of the bags have been heat sealed by the units B, the bags are presented to the stacking machine of the invention, which includes gripping units D on a stacking conveyor E and whereby the bags are carried to a stacking station F at which point the gripping units D are opened to release the bags in a manner causing them to be aligned in an orderly stack.

The heat sealing units B and the drum C are constructed in the manner fully described in said Patent No. 2,762,271. Therefore, it will suffice for the purposes of the present disclosure to explain that each of the heat seal units B comprises an electrically heated bar 20 (Figs. 4-8) mounted on the drum C in parallel relation to the axis thereof, and a clamp 22 fixed to a shaft 24 rotatably mounted on the drum C in position adjacent and parallel to the bar 20. A cam follower 26 is operatively connected by an arm 27 (Fig. 3) to the shaft 24 and cooperates with a cam groove 28 in a plate cam 29 adjacent one end of the drum to pivot the clamp 22 toward and away from the bar 20 at the appropriate times. A tucking plate 30 (Figs. 4-8) is fixed to the drum C, parallel to and adjacent the rearmost portion of the bar 20, when considered with respect to the direction of rotation of the drum C, and projects radially outward from said drum.

The drum C is provided with two stub shafts 32 and 34, one fixed to each end of the drum and projecting outwardly therefrom (Figs. 2 and 3). The stub shafts 32 and 34 are rotatably mounted in bearings 33 and 35 fixed to side frame members 36 and 38, respectively.

As best seen in Figs. 3 and 4, a second drum 40 is mounted above the drum C. The drum 40 is provided with two outwardly projecting hubs 42 and 44 rotatably supported in two bearings 46 and 48 mounted on the side frame members 36 and 38, respectively.

The stacking conveyor E comprises a pair of endless chains 50 and 52 (Figs. 2 and 3), and a plurality of cross bars 54 (Figs. 2, 3 and 4) extending therebetween. The chain 50 is trained around a drive sprocket 56 fixed to the hub 42 of the drum 40 and around three idler sprockets 58, 60 and 62 in the manner shown in Fig. 4. Similarly, the chain 52 is trained around a drive sprocket 45 64 (Fig. 3) fixed to the hub 44 of the drum 40 and idler sprockets 66, 68 (Fig. 2) and 69 (Fig. 3). The idler sprockets 58 and 66 are mounted on a shaft 70 extending transversely between and rotatably mounted in two side plates 71 and 72 fixed to the side frame members 50 36 and 38, by pairs of brackets 73 (Fig. 2) and 74 (Fig. 1), respectively. Similarly, the sprockets 60 and 68 are fixed to a shaft 79 extending transversely between the plates 71 and 72 and supported by two plates 83 and 85 (Figs. 1 and 2) adjustably secured to the plates 55 71 and 72, respectively. The plates 83 and 85 are movable vertically to adjust the slack in the conveyor belt E. The sprockets 62 and 69 are fixed to a shaft 80 extending transversely between and rotatably mounted in the side plates 71 and 72.

60 The links of the chain 50 are each formed with an integral, inwardly projecting tab 75 (Fig. 3). Similarly, the links of the chain 52 are each formed with an integral inwardly projecting tab 76. Each opposed pair of tabs 75 and 76 carries one of the bars 54 which is fastened thereto by machine screws 77 and 78.

The drum 40 and the drive sprockets 56 and 64 connected thereto are driven in timed relation with the drum C by a pair of meshing spur gears 81 and 82 (Fig. 1). The gear 81 is keyed to the hub 44 of the drum 40 and the gear 82 is keyed to the stub shaft 34 of the drum C. The gear 82 meshes with a drive gear 84 keyed to a shaft 86 rotatably mounted on the frame 87 of the bag making

machine. A sprocket 88 fixed to the shaft 86 is driven by a chain 90 in proper timed relation with the bag making machine, for example, in the manner fully described in said Patent No. 2,762,271.

The gripping units D are four in number, and they are equally spaced along the length of the stacking conveyor E in the manner shown in Fig. 4, the space between units being equal to one half the circumference of the drum C. All of the gripping units D are alike in construction and in their mounting to each of the chains 50 and 52. Therefore, only one unit and the mounting thereof at but one end will be described in detail. The main bar 100 of a gripping unit D is cut out at its end to form a recess 102 (Fig. 12) and a link-shaped block 104 positioned within the recess 102, is fastened to the bar 10 by a screw 106. The pins 108 and 110 that pivotally interconnect links of the chain 52 are elongated and extend into the block 104 to mount the bar 100 to the chain 52. The bar 100 is generally rectangular in shape with the outer, forward edge chamfered as indicated at 112 and with a rearwardly projecting shoulder 114 at its outer rear corner. An L-shaped block 116 is fastened to the bar 100 by a screw 118 and extends upwardly therefrom. A cylindrical end portion 122 of a square bar 120 projects through a suitable aperture in the block 116 to rotatably mount the bar 120 on the block 116. A collar 124 is fixed to the projecting end of the cylindrical end portion 122 of the bar 120 by a set screw 126. A torsion spring 128 surrounds the cylindrical end portion 122 of the bar 120 between the collar 124 and the block 116. One end of the spring 128 is fixed to the collar 124 and the other end to the block 116.

A clamping plate 130 is fixed to the bar 120 by a plate 132 and a plurality of screws 134 extending through suitable apertures in the plate 132 and slots 136 in the upper edge of the clamping plate 130 and threaded into the bar 120. The torsion spring 128 tends to rotate the bar 120 in a clockwise direction as viewed in Fig. 11 to urge the lower portion of the clamping plate 130 toward the rearwardly projecting shoulder 114 on the bar 100.

An arm 140 is fixed to the bar 120 by a screw 142 and extends forwardly therefrom. The arm 140 carries at its forward end a stub shaft 144 on which a cam follower roller 146 is rotatably mounted. The roller 146 is adapted to ride on the cam surface of a cam 148 and be actuated thereby to rotate the bar 120 in a manner to move the clamping plate 130 away from the shoulder 114 against the action of the torsion spring 128.

Two cams 148 are provided within the space enclosed by the conveyor E, for actuating the rollers 146, one roller 146 being associated with each end of each bar 120. The cams 148 operate to open the gripping units D to permit engagement of the bags thereby. The cams 148 are mounted on a shaft 150 (Fig. 3), which projects outwardly through the hubs 42 and 44 of the drum 40 and is supported for rotational adjustment in suitable sockets provided in the caps 152 and 154 of the bearings 46 and 48, respectively. An adjusting arm 156 is fixed to each end of the shaft 150 and is engaged between two opposed timing set screws 158, only one of which is shown (Fig. 2).

A second pair of cams 160, only one of which is shown (Figs. 4 and 9), are arranged within the space enclosed by the conveyor E to open the gripping units to release the bags at the stacking station F. The cams 160 surround the shaft 79, a bearing 159 being interposed between the shaft 79 and each cam 160 to permit the shaft 79 to rotate while the cams remain motionless. Each cam 160 is rigidly secured to the associated adjusting plate 83 or 85, as the case might be, by a pin 161.

A pair of angle brackets 162 and 164 (Figs. 2 and 4) are attached to the plates 71 and 72, respectively, adjacent the lower rear corners thereof, and a horizontal stacking shelf 166 is supported on the brackets 162 and 164. The shelf 166 is provided with a central, longitudinally extending groove 168 in its upper surface. A backing unit

170 (Fig. 4) rests on the shelf 166 with a downwardly projecting flange 172 thereof received in the groove 168. The backing unit 170 is provided with a vertical plate 174 adapted to abut the outermost bag in a stack being formed on the shelf 166 and support all the bags comprising the stack in an upright position.

All of the conveyor bars 54, the gripper bars 100 and the gripping plates 130 are provided with a plurality of transversely spaced, longitudinally aligned slots extending in the direction of movement of the stacking conveyor E (Figs. 2, 3 and 10). A plurality of stripping belts 180 are adapted to lie in said slots and travel with the conveyor. As the conveyor E bends around the sprockets 60 and 68 adjacent the stacking station F, and the gripper units D are released by the cams 160, the stripper belts 180 continue in a straight line, thus separating from the conveyor E to strip the bags therefrom. The stripper belts 180 then bend around a grooved pulley 182 rotatably mounted on a shaft 184 (Figs. 2 and 4) extending between the plates 71 and 72 below the level of the stacking shelf 166. The belts 180 then travel over another grooved pulley 186 (Fig. 4) rotatably mounted on the hereinbefore mentioned shaft 80, and again seat in the slots in the conveyor E as the conveyor E approaches the drive sprockets 56 and 64. The stacking shelf 166 is provided with a forwardly projecting plate 188 (Fig. 4), having a plurality of suitable apertures through which the belts 180 pass.

An automatic counting mechanism 189 is provided to divide the bags being stacked into groups each containing a predetermined number of bags. This counting mechanism comprises a bevel gear 190 (Fig. 1) fixed to the previously described shaft 79 and meshing with a companion bevel gear 192 fixed to a shaft 194 journaled on the plate 85. A worm 196 on the shaft 194 meshes with a worm gear 198. A cam 200 fixed to the gear 198 is adapted to actuate an arm 202, which is pivotally mounted at 203 to the plate 85, to actuate a microswitch 204.

The microswitch 204 is interposed in the electrical circuit (not shown) of a solenoid 206 (Fig. 2) fixed to the plate 72. The plunger 208 of the solenoid 206 is connected to a yoke 210 slidably mounted on two guide rods 212 and 214. A plate 216 connects the outer ends of the rods 212 and 214 and limits the outward movement of the yoke 210. The ends of the yoke 210 are split and provided with apertures to slidably receive two rods 220 and 222. Two transversely extending studs 224 and 226, respectively, are provided to squeeze the split ends and thereby clamp the yoke 210 to said rods. The rods 220 and 222 extend through suitable apertures in the plate 72 and carry on their inner ends an angle member 228. A pair of coil springs 230 and 232 surround the rods 220 and 222, respectively, between the yoke 210 and the plate 72 and normally urge the plate 228 toward the left as viewed in Fig. 2.

The pitch diameters of the sprockets 60 and 68 are one half the pitch diameters of the drive sprockets 56 and 64. Hence the shaft 79 rotates at twice the speed of the drum 40, making one revolution for each bag delivered to the stacking station F. The worm 196 and the worm gear 198 are so proportioned that the shaft 79 makes a predetermined number of revolutions for each revolution of the gear 198. Each time the gear 198 makes a complete revolution, the microswitch 204 is actuated to momentarily energize the solenoid 206 to move the angle member 228 to the right as viewed in Fig. 2, and the edge thereof pushes one or more bags out of line with the remaining bags stacked on the shelf 166, thus dividing the accumulating stack into groups each containing a predetermined number of bags.

In the operation of the device, the leading edge of a bag G clamped by a heat seal unit B approaches the top of the drum C as illustrated in Fig. 6. The bag G is draped over the tucking plate 30 in the manner shown.

The gripper assembly D on the stacking conveyor E is simultaneously approaching the bottom of the drum 40. As the gripping assembly D approaches the heat seal unit B it is opened by the cams 148. In Fig. 7 the elements are illustrated as having progressed until the heat seal unit B and the gripping unit D are in register with each other. In this position the tucking plate 30 is thrusting a fold or tuck 234 between the projecting shoulder 114 on the bar 100 and the clamping plate 130 of the gripping unit. The roller 146 is leaving the cam 148 and the plate 130 is being urged toward the shoulder 114 by the torsion springs 128 (Figs. 10 and 12) to grip the tuck 234. The shaft 24 of the heat seal unit B has been rotated slightly by the action of the cam groove 28 to release the bag from the heat seal clamp 22.

As the elements move to the positions illustrated in Fig. 8, the tucking plate 30 is withdrawn from between the shoulder 114 and the plate 130 of the gripping unit D leaving the tuck 234 of the bag securely clamped therebetween. Accordingly, as the conveyor E advances, the bag is carried by the gripping unit D until it reaches the stacking station F at which point (Fig. 9) the cam 160 opens the gripping unit, causing the same to release the tuck 234. The bag is then carried downwardly into contact with the stacking shelf 166 by frictional contact with the bars 54 of the stacking conveyor F, and the stripper belts 180 peel the bag off the bars 54 so that the bars can follow their arcuate path about the shaft 79 without carrying the bag with them. In this manner, the bag is deposited onto the stacking shelf 166 in a vertical plane between the backing unit 170 and the conveyor E.

Since the leading edge of each gripping unit is chamfered as indicated at 112, it presents an inclined surface to the uppermost edge of a bag previously delivered to the stacking shelf, in the event that said uppermost edge tends to block entry of the next succeeding bag into position between the conveyor E and the previously stacked bags. Hence, the next succeeding bag approaching the stacking station F can pass between the preceding bag and the conveyor E without mousing or otherwise damaging either bag.

As succeeding bags are thus delivered to the stacking station F, they accumulate in an orderly stack behind the backing unit 170, which is pushed away from the conveyor E by the bags as the number of bags in the stack increases. When the apparatus has handled a number of bags corresponding to the number of times the shaft 79 turns for each full revolution of the worm wheel 198, the automatic counting mechanism 189 will be actuated as hereinbefore described, causing at least one bag to be laterally offset in the accumulated stack, thus facilitating removal from the stack of any desired number of bags.

In view of the fact that the plate 130 and the shoulder 114 which constitute the opposed jaws of a gripping unit D extend throughout approximately the entire width of the conveyor E, the stacking machine of the invention is capable of handling bags of a wide variety of widths without requiring adjustment of any of its parts because the wide jaws 114 and 130 can handle either wide or narrow bags with equal efficiency. Since each bag is deposited onto the stacking shelf 166 with the full length of the bag in a vertical position, corresponding to the position that it will occupy within the stack, the stacking machine of the invention is adapted to handle bags of any length up to and including the distance between gripping units D of the conveyor E.

While a preferred embodiment of the present invention is described herein, it should be noted that various changes may be made therein without departing from the spirit of the invention as defined in the appended claims.

Having thus described my invention, what I claim and desire to secure by Letters Patent is:

1. A stacking mechanism comprising a movable conveyor made up of two parallel endless chains having

their opposing links interconnected by a plurality of cross bars in side-by-side relation with each other, means for moving the conveyor, a plurality of spaced apart gripping units on said conveyor in timed relation with the movement thereof, means adjacent said conveyor for actuating said gripping units to receive and grip said bags, guide means for said conveyor causing one portion of its travel to be vertically downward for a distance as great as the length of one of said bags, means adjacent the lower end of said vertical portion of the path to actuate said gripping units to release the bags, a stacking shelf adapted to receive the bags when released from said gripping units, said cross bars having therein a plurality of notches defining grooves in said conveyor extending longitudinally thereof, and a plurality of stripping belts received in said grooves and traveling with said conveyor.

2. A stacking mechanism comprising a movable conveyor made up of two parallel endless chains having their opposing links interconnected by a plurality of cross bars in side-by-side relation with each other, means for moving the conveyor, a plurality of gripping units on said conveyor at spaced intervals therealong, each of said gripping units including a first bar fixed to the chains of said conveyor, a second bar mounted parallel to said first bar and rotatable about its own axis, a plate fixed to said second bar and movable toward and away from said first bar by rotation of said second bar, spring means urging said plate toward said first bar, a cam follower arm fixed to said second bar, a cam follower on said arm, means for feeding bags to said conveyor in timed relation with the movement thereof, first cam means mounted adjacent said conveyor in position to be engaged by said cam follower to actuate said gripping units to receive and grip the bags, guide means for said conveyor causing one portion of its path to be vertically downward for a distance as great as the length of one of said bags, second cam means mounted adjacent the lower end of said vertical path in position to be engaged by the cam follower to actuate said gripping units to release the bags, a stacking shelf adapted to receive the bags when released from said gripping units, and stripping belts traveling with said conveyor but separable therefrom at the lower end of said downward path to strip the bags from said conveyor.

3. A stacking mechanism comprising an endless conveyor made up of two parallel endless chains having their opposing links interconnected by a plurality of cross bars in side-by-side relation with each other, a plurality of gripping units on said conveyor spaced at equal distances therealong, each of said gripping units including a first bar fixed to the chains of said conveyor, a second bar mounted parallel to said first bar and rotatable about its own axis, a plate fixed to said second bar and movable toward and away from said first bar by rotation of said second bar, spring means urging said plate toward said first bar, a cam follower arm fixed to said second bar, a cam follower on said arm, means for feeding bags to said conveyor in timed relation with the movement thereof, first cam means mounted adjacent said conveyor in position to be engaged by said cam follower to actuate said gripping units to receive and grip the bags, guide means for said conveyor causing one portion of its path to be vertically downward for a distance as great as the length of one of said bags, second cam means mounted adjacent the lower end of said vertical path in position to be engaged by the cam follower to actuate said gripping units to release the bags, a stacking shelf adapted to receive the bags when released from said gripping units, said cross bars having a plurality of notches therein defining grooves in said conveyor extending longitudinally thereof, and a plurality of stripping belts received in said grooves and traveling with said conveyor.

4. A stacking mechanism comprising an endless conveyor made up of two parallel endless chains having their opposing links interconnected by a plurality of cross bars in side-by-side relation with each other, a plurality of gripping units on said conveyor spaced at equal distances therealong, each of said gripping units including a first bar fixed to the chains of said conveyor, a second bar mounted parallel to said first bar and rotatable about its own axis, a plate fixed to said second bar and movable toward and away from said first bar by rotation of said second bar, spring means urging said plate toward said first bar, a cam follower arm fixed to said second bar, a cam follower on said arm, means for feeding bags to said conveyor in timed relation with the movement thereof, first cam means mounted adjacent said conveyor in position to be engaged by said cam follower to actuate said gripping units to receive and grip the bags, guide means for said conveyor causing one portion of its path to be vertically downward for a distance as great as the length of one of said bags, second cam means mounted adjacent the lower end of said vertical path in position to be engaged by the cam follower to actuate said gripping units to release the bags, a stacking shelf adapted to receive the bags when released from said gripping units, said cross bars having a plurality of notches therein defining grooves in said conveyor extending longitudinally thereof, and a plurality of stripping belts received in said grooves and traveling with said conveyor.

veyor but separable therefrom at the lower end of said vertical path to strip the bags from said conveyor.

4. Mechanism for stacking bags of cellophane or like yieldable material, comprising a conveyor, means for moving said conveyor in an endless path of travel, said means including a plurality of sprockets over which said conveyor is trained, said conveyor having a downwardly moving vertical portion defined by and extending between the horizontal planes of the axes of a pair of said sprockets disposed in vertically spaced relation, a plurality of grippers on said conveyor at spaced intervals therealong, means for feeding bags to said conveyor in timed relation with the movement thereof, means adjacent said conveyor for actuating said gripping units to receive and grip the bags, cam means adjacent the lower end of said vertical conveyor portion for actuating said gripper units to release the bags with the major length thereof directly engaging said vertical conveyor portion, and a stacking shelf disposed beneath the lower end of said downwardly moving vertical conveyor portion for receiving and stacking the released bags.

5. Mechanism for stacking bags of cellophane or like yieldable material, comprising a conveyor, means for moving said conveyor in an endless path of travel, said means including a plurality of sprockets over which said conveyor is trained, said conveyor having a downwardly

5 10 15

20 25

moving vertical portion defined by and extending between the horizontal planes of the axes of a pair of said sprockets disposed in vertically spaced relation, a plurality of grippers on said conveyor at spaced intervals therealong, means for feeding bags to said conveyor in timed relation with the movement thereof, means adjacent said conveyor for actuating said gripping units to receive and grip the bags, cam means adjacent the lower end of said vertical conveyor portion for actuating said gripper units to release the bags with the major length thereof directly engaging said vertical conveyor portion, a stacking shelf disposed beneath the lower end of said downwardly moving vertical conveyor portion for receiving and stacking the released bags, and stripping belts traveling with said conveyor and separable therefrom at the lower end of said vertical portion thereof for stripping the bags from said conveyor.
